PUNCHING MACHINE

Hans P. Luhn, Armonk, N. Y., assignor to International Business Machines Corporation, New York, N. Y., a corporation of New York

Application December 29, 1945, Serial No. 637,857

7 Claims. (Cl. 164—113)

1

This invention relates to record card punching machines and more particularly to punching machines of the step-by-step type.

The principal object of the invention resides in the provision of improved mechanism for advancing a record card past a row of punches.

A further object is to provide a feed mechanism which will step a record card rapidly and positively from column to column for rapid punching in successive columns.

Another object is to provide means for positively holding the card carriage upon the columnar positioning of the card to be punched.

Another object is to provide a feed mechanism operable to advance a record column by column in either of two opposite directions.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a plan view of the punching machine showing the general arrangement and location of the keyboard.

Fig. 2 is a sectional elevation taken substantially along lines 2—2 of Fig. 1.

Fig. 3 is an enlarged detail in plan view taken on lines 3—3 of Fig. 2.

Fig. 4 is a section on lines 4—4 of Fig. 2 showing the oscillating control devices for the feed.

Fig. 4a is a detail on lines 4a—4a of Fig. 4.

Fig. 5 is a section on lines 5—5 of Fig. 2, showing the release control devices for the feed.

Figs. 6 and 7 are details showing different operating positions of parts shown in Fig. 5.

Fig. 8 is a detail showing the punch operating magnet and related contact devices.

Fig. 9 is a wiring diagram of the essential circuit connections of the machine.

The punching mechanism is of the type wherein in a row of punches 10 (Figs. 1 and 2) is provided, past which a record card 11 is moved step by step. This card is provided with columns of punching positions arranged in rows designated 12, 11, 0, 1, 2, 3, 4, 5, 6, 7, 8 and 9 in line with corresponding punches 10. The card 11 is placed on a table 12 (Figs. 1 and 4) where it is guided by rails 13 against lateral displacement. At its left and right ends, the card is engaged by fingers 14 and 15 respectively. These fingers are secured to a carriage comprising a bar 16 to which are fastened guide blocks 17 and 18 (Figs. 2 and 4) slotted to slide on a stationary guide rail 19.

2

Through the mechanism to be described, the carriage is moved along rail 19 to present the card columns to the row of punches 10. Before describing this mechanism, a brief description will be given of the punching devices which are well known, being similar to those shown in the patent of F. L. Lee et al. No. 1,772,186. Resting on the top of each punch 10 is the left end of an interposer 20 (Fig. 2) which is horizontally 5 slidable by a bell crank connection 21, through a key 22. When key 22 is depressed, interposer 20 slides to the left against the tension of spring 23, and its left end of greatest height moves under a bar 24 on a plate 25 pivoted at 26. At the same 10 time, the side of a notch 27 engages and rocks a plate 28 about pivot 29. A hooked link 30 (Fig. 8) engaging the plate is thereby drawn to the left to close a pair of contacts 31. These contacts (Fig. 9) close a circuit between current lines 32, 33 to energize punch magnet 34 (Fig. 8), and as a result armature 35 is operated to rock bellcrank 36 through link 37 and through link 38 plate 25 is rocked counterclockwise about its 15 pivot 26 to force bar 24 down against the advanced interposer 20 and push the related punch through the card 11 against the punch restoring spring 39. When plate 25 is rocked, an extension 40 thereon (Fig. 8) will tilt link 30 out of hooked engagement with plate 28 so that the contacts 31 spring open under their own tension to break the punch magnet circuit and the parts restore to their initial positions.

As shown in the patent referred to, the keys 22 may also be magnetically operated, but for purposes of simplicity in the present application only the manual operating mechanism is shown.

Carriage block 17 has integral therewith six depending pins or teeth 42 (Figs. 2 and 3) normally engaged in rack teeth 43 of a plate 44 which thus substantially positively hold the carriage in position. Plate 44 has secured thereto spaced blocks 45 pivoted on a rod 46, the left end of which has a lever 47 secured thereto (Fig. 4) with a depending arm 48 engaged by a latch 49. The latch is free on a rod 50 about which there is coiled a spring 52 whose ends engage a pin 51 in latch 49 and also a pin 53 in a lever 54 also free on rod 50 (see Fig. 4a). The lower end of spring 52 normally urges latch 49 into engagement with arm 48 by bearing upwardly against pin 51. Lever 54 is also provided with a wire spring 55 which holds the lever 54 and its pin 53 in the position shown in Fig. 4. The lever 54 has link connection 56 with an arm 57 integral with armature 58 of a magnet 59.

When this magnet is energized, lever 54 is rocked counterclockwise and its pin 53 will push the lower end of spring 52 away from pin 51 of latch 49, so that the upper end of spring 52 now bears down on pin 51 and tends to turn latch 49. However, this tension is not sufficient to rock the latch because arm 48 is biased counterclockwise with considerable force, creating enough frictional resistance at the latching point to prevent movement of the latch by spring 52. This force is applied by a coil spring 60 (Fig. 2) which has one end anchored to the rod 46 and the other to a post 61 in base plate 62.

In Figs. 3 and 4 lever 47 is shown as riding the periphery of a pin 63 mounted eccentrically on a shaft 64. This shaft has a bevel gear 65 at its opposite end driven by a bevel gear 66 secured to a shaft 67 to which there is secured a pulley 68 driven by belt and pulley connection 69 from a constantly running motor 70.

The action is such that during each revolution of shaft 64 eccentric pin 63 engages lever 47 and rocks it slightly to release the tension against latch 49. If at the time of engagement lever 54 is in rocked position, with spring 52 biasing latch 49 counterclockwise as viewed in Fig. 4 the latch will rock out of engagement with arm 48, so that the arm and lever 47 with their shaft 46 will follow eccentric pin 63 under the influence of coil spring 60. Such rocking of shaft 46 will carry plate 44 with it to the positions shown in Figs. 6 and 7 to disengage rack teeth 43 from carriage pins 42.

While the shaft 46 is rocked, lever 54 is returned to its initial position where latch 49 will reengage arm 48. If arm 54 is maintained in its rocked position, as will be explained, shaft 46 will be repeatedly oscillated, once for each revolution of shaft 64.

Referring now to Fig. 3, shaft 46 has freely pivoted thereon spaced blocks 71 in each of which there is a screw 72 riding in a slot 73 of a plate 74 (see Fig. 2). The plate thus serves to connect the blocks 71 for unitary rotary movement. A spring 75 (Fig. 3) anchored to one of the blocks 45 and one of the blocks 71 serves to bias the plates 44 and 74 in opposite directions toward one another as viewed in Fig. 3 and adjustable screws 76 threaded in plate 74 and abutting blocks 71 serve to limit the space between the two plates.

The upper edge of plate 74 is provided with rack teeth 77 having the same pitch as teeth 43 in plate 44. When shaft 46 is rocked as explained, the plate 74 also rocks while maintaining its spaced relationship with plate 44. The extent of rocking is such that as teeth 43 release carriage pins 42, teeth 77 move into engagement with the pins with the result that the pins are alternately engaged by the two opposed sets of rack teeth. Also, it is to be noted that each set of rack teeth engages the pins before the other set has completely released them so that the pins are under control of one or the other set of rack teeth at all times. Fig. 7 shows the rocked position of the parts wherein the pins 42 are in engagement with rack teeth 77 and out of engagement with rack teeth 43.

While the pins 42 are engaged in rack teeth 77, the plate 74 is shifted toward the left as viewed in Fig. 2 carrying the carriage pins 42 therewith, and while in such left hand position the plates are rocked back to the position of Fig. 5. As a result, the pins 42 are reengaged by rack teeth 43 with a one tooth or step ad-

vance. This step corresponds to the card column spacing so that the card 11 is thereby advanced one step to present the next column to the row of punches 10. To reciprocate plate 74, its right hand end (Fig. 2) is slotted at 80 to embrace an eccentric pin 81 on shaft 67, which eccentric pin is so positioned with respect to eccentric pin 63 (Fig. 4) that the proper timing is provided to shift plate 74 to the left while it is engaging pins 42 and to shift it back to the right after it has released the pins. To take up any slight play between slot 80 and eccentric pin 81 there is provided a spring 82 (Fig. 3), which extends between a block 45 and an angle 83 on plate 74 to constantly urge the plate toward the right.

The manner in which the stepping is controlled by and synchronized with the punching operation will now be explained. Punch bell crank 36 (Fig. 8), when operated to effect punching, closes a pair of contacts 84 which in Fig. 9 energize a relay 85 whose armature has an adjustable dash pot 86 connected thereto to slow down the operation of the relay. This dash pot is so adjusted that contacts 85a of the relay close just before the contacts 84 reopen, at which time the punches 10 will have been retracted from the card 11. On rod 46 (Fig. 9) is secured an arm 87 which opens a pair of contacts 88, when the rod is rocked. A latch 120 is arranged to engage and hold the contacts 88 open but is normally prevented from doing so by magnet 121 which is energized through the circuit from line 32, contacts 85b and magnet 121 to line 33.

When contacts 85a close, there will be a circuit from line 32, contacts 85a, and contacts 88 to space magnet 59 and line 33. As a result, arm 54 (Fig. 4) is operated and latch 49 therewith to release lever 47, so that the stepping racks may oscillate to advance the carriage. The incidental opening of contacts 85b has deenergized magnet 121 so that, when rod 46 is rocked, contacts 88 open and are engaged by latch 120 so that no repeat operations of the space magnet 59 can occur.

During the advance, contacts 84 of the punch magnet fully open, deenergizing relay 85 whose contacts 85a open and contacts 85b close to re-energize magnet 121 and release contacts 88. This operation occurs for each punch key operation to step the carriage as an incident to each punching operation.

When it is desired to effect a step of advance without punching, a key 89 (Fig. 9) is depressed to momentarily close contacts 90, to complete a circuit from line 32, contacts 90, contacts 88 and space magnet 59 to line 33. As a result, the carriage is stepped ahead one tooth or card column.

It will be apparent that if key 89 is held depressed, magnet 59 will be repeatedly energized and thus a rapid step-by-step advance of the carriage may be effected. An audible click accompanies each step of advance occasioned by the engagement of reciprocating teeth 77 with pins 42, so that if, for example, it is desired to step the carriage ten columns, key 89 is held until ten clicks have occurred and then released before another is heard.

In Fig. 9 the motor 70 is conventionally represented as a shunt wound reversing motor with a reversing switch 92 whereby the motor may be rotated in either direction. A main switch 93 is also provided. With the motor running in one direction, the card carriage will be driven from left to right as viewed in Fig. 2 and punching

will take place on the card from left to right.

With the motor running in reverse direction, the carriage is initially in its most left hand position and operation of the space magnet will cause the carriage to advance step by step from left to right. This is so because now the reciprocating stroke of plate 74 toward the right occurs while the shaft 46 is rocked and the stroke of plate 74 toward the left occurs while the plate is out of engagement with pins 42. In other words, the combinational action of rocking rod 46 and reciprocating plate 74 is now occurring in reverse order, and the same positive drive will step the carriage backward.

It is thus seen that depending upon the direction of drive obtained by simple reversing switch means, the operator may place a card in the carriage and punch either from left to right or from right to left.

Provision is made for releasing the carriage from the feed mechanism so the carriage may be directly moved manually to either extreme position for insertion or removal of cards. Referring to Fig. 5, the plate 44 has a depending arm 95 integral therewith and extending through an opening in base plate 62. Beneath arm 95 is a latch 96 pivoted on a rod 97. Also pivoted on rod 97 is a lever 98 connected by a link 99 to an arm 100 integral with the armature of release magnet 101. The right arm of lever 98 carries a pin 102 and latch 96 carries a pin 103. A spring 104 coiled around rod 97 engages pins 102 and 103 to hold latch 96 normally in the position shown in Fig. 5. In such position, the latch is out of the path of the end of arm 95 as the latter rocks between the positions of Figs. 5 and 7.

Energization of release magnet 101 will rock lever 98 against its restoring spring 105 and through spring 104 will urge latch 96 in a counterclockwise direction. If shaft 46 is now rocked to tilt plates 44, 74 to the position of Fig. 7, latch 96 will snap behind arm 95 and lock plate 44 in its rocked position so that plate 74 returns alone to its initial position, leaving the parts in the relationship shown in Fig. 6, where the carriage pins 42 are not engaged by either rack and accordingly the carriage may be shifted as by finger piece 106 (Fig. 4) in either direction and to any extent.

In Fig. 9 the release operation is initiated by a key 107, which upon depression first closes contacts 108 to energize release magnet 101 and immediately thereafter closes contacts 109 to energize the space magnet 59 through the circuit from line 32, contacts 109, contacts 88 and magnet 59 to line 33. The key depression is momentary to bring about only one oscillation of the rack plates and after the plate 44 is latched it will remain so, due to the frictional engagement between arm 95 and latch 96.

To rock plate 44 back to its effective position, it is necessary to energize space magnet 59 through key 88 which will result in easing the pressure of arm 95 against latch 96 so that the light spring 104 may then rock the latch back to its position of Fig. 5.

In Fig. 1 a spring 110 may be removably connected between a pin 111 on the card carriage and a fixed post 112. Then, when the release key 107 is operated, the carriage will be automatically drawn back to its right hand position. This location of spring 110 is advantageous where punching is effected only in columns of the left hand section of the card, in which case

the card travels only a short distance back to its starting position for removal.

By unhooking spring 110 from post 112 and connecting it between pin 111 and a second fixed post 113, the carriage will automatically shift to the left upon operation of the release key 107. This position of spring 110 is advantageous where punching takes place in columns extending across most of the card area, so that the card upon release shifts the shorter distance to its extreme left hand position for removal.

The selectivity of the direction of step-by-step feeding through the motor reversing switch 92 and the direction of the release movement 15 enables the operator to establish the conditions of operation best suited for the particular punching arrangement being effected.

While there have been shown and described and pointed out the fundamental novel features 20 of the invention as applied to a single modification, it will be understood that various omissions and substitutions and changes in the form and details of the device illustrated and in its operation may be made by those skilled in the art 25 without departing from the spirit of the invention. It is the intention therefore to be limited only as indicated by the scope of the following claims.

What is claimed is:

- 30 1. In a record card punching machine, a row of punches, an elongated card carriage movable transversely to said row of punches, actuating means for the punches, a pin in said carriage, a locking member engageable with said pin to hold the carriage positively in punching position, a feeding member, means to positively actuate the feeding member in either direction of movement of the carriage, said feeding member being positively engageable with the pin but normally out of engagement therewith, means controlled by said punch actuating means and operable as an incident to the operation thereof for disengaging said locking member from the pin and concurrently engaging the feeding member therewith at one extremity of the stroke of said feeding member, said last named means causing reengagement of the locking member with the pin and disengagement of the feeding member therefrom at the other extremity of the 40 stroke of the feeding member and settable means for positioning said carriage relative to said punches, whereby the carriage will be shifted in either direction a distance determined by the stroke of the feeding member and locked in shifted position.
- 45 2. In a record card punching machine, a row of punches, a card carriage movable transversely to said row of punches, card holding means on said carriage, actuating means for the punches, a locking member normally engaging said carriage to hold it positively in punching position against displacement in either direction, a feeding member, means for reciprocating said feeding member in the direction of movement of the 50 carriage, said feeding member being engageable with the carriage but normally out of engagement therewith, means controlled by said punch actuating means and operable as an incident to the operation thereof for disengaging said locking member from the carriage and concurrently engaging the feeding member therewith at one extremity of the stroke of said feeding member, said last named means causing reengagement of the locking member with the carriage and disengagement of the feeding member therefrom.
- 55 3. In a record card punching machine, a row of punches, a card carriage movable transversely to said row of punches, card holding means on said carriage, actuating means for the punches, a locking member normally engaging said carriage to hold it positively in punching position against displacement in either direction, a feeding member, means for reciprocating said feeding member in the direction of movement of the 60 carriage, said feeding member being engageable with the carriage but normally out of engagement therewith, means controlled by said punch actuating means and operable as an incident to the operation thereof for disengaging said locking member from the carriage and concurrently engaging the feeding member therewith at one extremity of the stroke of said feeding member, said last named means causing reengagement of the locking member with the carriage and disengagement of the feeding member therefrom.
- 65 4. In a record card punching machine, a row of punches, a card carriage movable transversely to said row of punches, card holding means on said carriage, actuating means for the punches, a locking member normally engaging said carriage to hold it positively in punching position against displacement in either direction, a feeding member, means for reciprocating said feeding member in the direction of movement of the 70 carriage, said feeding member being engageable with the carriage but normally out of engagement therewith, means controlled by said punch actuating means and operable as an incident to the operation thereof for disengaging said locking member from the carriage and concurrently engaging the feeding member therewith at one extremity of the stroke of said feeding member, said last named means causing reengagement of the locking member with the carriage and disengagement of the feeding member therefrom.

at the other extremity of the stroke of the feeding member and settable means for selecting the direction of shift of said carriage, whereby the carriage will be shifted a distance determined by the stroke of the feeding member and locked in shifted position.

3. In a record card punching machine, a row of punches, an elongated card carriage movable transversely to said row of punches, card holding means on said carriage, actuating means for the punches, a feeding member, means for positively reciprocating said feeding member in either direction of movement of the carriage, said feeding member being engageable with the carriage to positively actuate the same but normally out of engagement therewith, means controlled by said punch actuating means and operable as an incident to the operation thereof for positively engaging said feeding member with the carriage at one extremity of the stroke of said feeding member, said last named means causing disengagement of the feeding member at the other extremity of its stroke, whereby the carriage will be positively shifted a distance determined by the stroke of the feeding member.

4. In a record card punching machine, a row of punches, a card carriage slideable transversely to said row of punches, actuating means for the punches, a feeding member, means for reciprocating said feeding member in either direction of movement of the carriage, said feeding member being engageable with the carriage but normally out of engagement therewith, means controlled by said punch actuating means and operable as an incident to the operation thereof for engaging said feeding member with the carriage at one extremity of the stroke of said feeding member, said last named means causing disengagement of the feeding member at the other extremity of its stroke and settable means for selecting the extremity of the stroke at which engagement is to occur whereby the carriage will be selectively shifted in either direction a distance determined by the stroke of the feeding member.

5. In a machine of the class described, a recording element, a record supporting carriage slideable transversely to said recording element, actuating means for the recording element, a feeding member, means for reciprocating said

feeding member in the direction of movement of the carriage in either direction, said feeding member being engageable with the carriage but normally out of engagement therewith, means controlled by said actuating means and operable as an incident to the operation thereof for engaging said feeding member with the carriage at one extremity of the stroke of said feeding member, said last named means causing disengagement of the feeding member at the other extremity of its stroke and settable means for selecting the extremity of the stroke at which engagement is to occur whereby the carriage will be shifted in either direction a distance determined by the stroke of the feeding member.

6. The invention set forth in claim 5, in which a locking member is provided to lock the carriage in position, said actuating means being effective to disable the locking member prior to the movement of the carriage.

7. In a machine of the class described, a row of punches, a card carriage selectively movable in either direction transversely to said row of punches, means normally effective to lock the carriage against movement, power means for moving the carriage in either direction, each operation thereof advancing the carriage one step, key controlled means for causing a selected punch to penetrate the card and then withdraw therefrom, means operative upon withdrawal of the punch for concurrently disabling said locking means and rendering the power means effective to advance the card in either direction.

35 HANS P. LUHN.
